REFILL LEAD CONTAINER OR SIMILAR ARTICLE

Benjamin W. Hanle, Elizabeth, N. J., assignor to
Eagle Pencil Company, a corporation of Delaware

Application October 22, 1953, Serial No. 27,279

Term of patent 14 years

(Cl. D74—21)

To all whom it may concern:

Be it known that I, Benjamin W. Hanle, a citizen of the United States and residing at Elizabeth, county of Union, and State of New Jersey, have invented a new, original, and ornamental Design for a Refill Lead Container or Similar Article, of which the following is a specification, reference being had to the accompanying drawings, forming part thereof, and in which

Fig. 1 is a perspective view with parts broken away, showing my new design of refill lead container,

Fig. 2 is a view similar to Fig. 1 showing a front elevation thereof, and

Fig. 3 is a top plan view thereof.

I claim:

The ornamental design for a refill lead container or similar article, substantially as shown.
